UNITED STATES PATENT OFFICE.

GEORGE MAX ESTERLY AND GEORGE W. ESTERLY, OF WASHINGTON,
DISTRICT OF COLUMBIA.

DREDGING APPARATUS.

SPECIFICATION forming part of Letters Patent No. 651,781, dated June 12, 1900.

Application filed April 12, 1900. Serial No. 12,579. (No model.)

To all whom it may concern:

Be it known that we, GEORGE MAX ESTERLY and GEORGE W. ESTERLY, citizens of the United States, residing at Washington, in the 5 District of Columbia, have invented certain new and useful Improvements in Dredging Apparatus, of which the following is a description, reference being had to the accompanying drawings, and to the letters of reference marked thereon.

The object of our invention is to provide apparatus by means of which sand or other soil lying so near shore or in so shoal water as to be inaccessible to the ordinary floating dredge 15 may be reached and dredged out; and the apparatus which we have invented is particularly adapted and intended for the recovery of precious-metal-bearing sands lying near shore, but below low-water mark.

20 Our invention consists in hydraulic dredging apparatus, consisting of a suction-pump and suction-pipe connected with the pump carried by a vehicle adapted to be moved and to be held in a stationary position on 25 the ground or on piles, trestle-work, or other firm base, the suction-pipe being adapted to extend out into the water and to be raised and lowered and swung in any direction, the vehicle carrying also a suitable source of 30 power by which the suction-pump may be operated, the movements of the suction-pipe effected, and the vehicle propelled, all as hereinafter described and shown in the accompanying drawings.

35 It is well known that the danger involved in anchoring a dredge or other vessel in the open sea in shoal water near a sandy beach is such as preclude the possibility of the use of floating dredges under such circumstances.

40 Precious-metal-bearing ores of great richness have in some instances been found beneath the surface of the open sea, so located that by reason of the shoalness of the water and the strength of the tidal currents and surf, 45 particularly during storms, they cannot be recovered by the use of floating dredges; nor can such sands be recovered to a practical extent by the use of the excavators of the bucket or scoop type mounted on vehicles adapted to travel upon the land, by reason of the fact that such excavators are not

adapted to extend out over the water more than a comparatively-short distance, by reason of the fact that in order to be effective in operation they must lift a very heavy mass 55 at each operation.

Our apparatus being mounted on a vehicle adapted to rest and travel upon a solid foundation is not liable to injury from tidal currents or surf and may be operated without 60 interruption even during storms, it being possible at any time, should the surf or currents become dangerously high, to run the vehicle back out of danger. Further, the material raised by our dredging apparatus is distributed 65 throughout the length of the suction-pipe instead, as in a bucket or scoop excavator, of being carried wholly at the end of the arm or boom. By reason of this fact and the further fact that the suction-pipe of our apparatus is provided at its end with a downwardly-extending section adapted to rest to 70 a greater or less extent upon the sand beneath the water, and thus afford more or less support to the suction-pipe we are enabled to 75 use a suction-pipe many times longer than could be used with an excavator of anything like the same size.

Our invention also consists in the specific constructions and combinations hereinafter 80 described, and particularly pointed out in the claims.

In the accompanying drawings, Figure 1 is a view in elevation of our dredging apparatus. Fig. 2 is a plan view of the same, the devices 85 for raising and lowering the boom being removed.

In the construction shown in the drawings, A is the vehicle, adapted to be moved on or held stationary on the ground or on piles, 90 trestle-work, or other firm base. As shown, the wheels are adapted to run on a track; but it is evident that if the ground or other base is sufficiently firm the track may be dispensed with and wheels having broad tires 95 may be substituted for the track-wheels shown. The framework of the vehicle A supports a turn-table C, on which the platform is adapted to rotate. This platform carries the operating devices of the apparatus, consisting of the suction-pump E, the suction-pipe F, and the motive power for operating 100

the pump and for effecting through suitable operating connections the necessary movements of the suction-pipe and for propelling the vehicle.

5 In the construction shown the suction-pipe F is carried by a boom G, which is hinged at H to the platform D, so as to be capable of being raised and lowered by the mechanism hereinafter described, but is not arranged to 10 swing on the platform.

The suction-pipe F has at its outer end a swinging section F', which carries at its lower end a suction-head F'', adapted to enter the sand or other soil to be dredged. This swinging section will to some extent be supported by the sand or other soil and will thus more or less sustain the outer end of the suction-pipe. A winch I and ropes or chains I' are provided, as shown, for swinging this section 15 of the suction-pipe. This winch is arranged to be operated by a workman standing near the peak of the boom, the boom being provided with a platform J, on which such workman may stand, and with a footboard J', by which 20 access to the platform may be readily gained. The suction-pipe is provided at the inner end of the boom with a swivel-joint L or other flexible joint, which will permit of the raising or lowering of the portion of the suction-pipe 25 carried by the boom.

The suction-pump E, which in the construction shown is a centrifugal pump of ordinary construction, discharges the sand and water into sluice-boxes, (not shown,) which may be 30 carried by the vehicle, by other vehicles on the same track, or may be arranged on the ground in any convenient manner.

The boom G, carrying the suction-pipe F, is raised and lowered by any convenient means 35 carried on the platform. The mechanism shown for this purpose consists of the engine M, arranged to drive, through suitable gearing M', a windlass N of ordinary construction, which through the ropes or chains N' 40 effects the raising and permits the lowering of the boom.

On the horizontal shaft O, driven by the engine P, are arranged bevel gear-wheels o and o', arranged to be clutched to the shaft 45 when desired. The gear o meshes with the circular rack R, carried by the vehicle-frame, and when operated effects a rotation of the platform to any extent desired. The gear o' 50 meshes with a bevel-gear on the vertical shaft S, carried by the vehicle-frame at the center rotation of the platform and operatively connected through suitable gearing with the axles of the vehicle.

It will be understood that the boiler and engine, the fuel-box U, and the water-tank V are so arranged on the platform as to counterbalance the weight of the boom and suction-pipe.

In operation, the tracks being laid as near 65 the shore as convenient, the apparatus is placed on them and through the engine P and gearing o' and S the vehicle is propelled to

the point desired. The platform is then rotated by means of the engine P and gearing o' and S and the boom lowered until the end 70 of the suction-pipe is brought into effective contact with the sand. The pump is then started. By operating the swinging section of the suction-pipe and by raising or lowering the boom and rotating the platform the sand 75 may be dredged from a large area, and by advancing the vehicle along the track the area which can be effectively dredged is still further increased.

If found necessary, a mechanical stirrer 80 may be used on the outer end of the suction-pipe for loosening up the sand. By making the suction-pipe F sufficiently strong it is evident that the boom G may be dispensed with and the suction-pipe in such case braced 85 and supported by the ropes or chains N', acting both as suction-pipe and boom.

We are aware that devices for handling coal ore and the like, consisting of an arm carrying a bucket or scoop mounted on a rotatable platform carried by a vehicle, the platform carrying also a motor and means operated thereby by which the bucket or scoop 90 may be operated, the platform rotated, and the vehicle propelled, are well known; but 95 such devices would not be capable of effective use for the purposes for which our device is intended, as has been above explained, and we do not claim such devices. We are also aware that it has been proposed to place upon 100 a float or boat a suction-pipe and suction-pump and means for raising and lowering the suction-pipe and for operating the suction-pump; but such a device is not capable of 105 effective use for the purpose for which our device is intended, as has been above explained, and we do not claim such a device.

Having thus described our invention, what we claim, and desire to secure by Letters Patent, is—

1. The combination with a vehicle, and a track or way on which said vehicle is adapted to travel, arranged on solid foundation along the shore of a body of water, of a platform carried by the vehicle and adapted to be rotated thereon, a suction-pump mounted on the platform, a suction-pipe having an end section thereof adapted to extend downward at an angle to the main portion of the pipe, connected with the suction-pump and carried 115 by the platform and projecting therefrom, and means mounted on the platform for rotating the platform, and for propelling the vehicle, whereby the dredging operation may be carried on in strong currents or surf; substantially as described.

2. The combination with a vehicle, of a platform carried thereby, and adapted to be rotated thereon, a suction-pump carried by the platform, a vertically-swinging boom carried by the platform, a suction-pipe having an end section thereof adapted to extend downward at an angle to the main portion of the pipe and adapted to be swung, carried by 120

the boom and connected with the suction-pump, and means carried by the platform for swinging the boom, operating the suction-pump, rotating the platform, and independent means for operating the swinging section of the pipe; substantially as described.

3. The combination with a vehicle, of a platform carried thereby and adapted to be rotated thereon, hydraulic dredging apparatus carried by the platform comprising a suction-pipe having an end section adapted to extend downward at an angle to the main portion of the pipe and adapted to be swung, a motor carried by the platform, and mechanism by which the motor operates the dredging apparatus, effects the rotation of the platform, and propels the vehicle, and independent means for swinging the end section of the suction-pipe; substantially as described.

4. The combination with a vehicle, of a platform carried thereby and adapted to be rotated thereon, hydraulic dredging apparatus carried by the platform, a motor carried by the platform arranged to operate the dredging apparatus, a horizontal shaft driven by the motor, a vertical shaft carried by the vehicle-frame, at the center of rotation of the platform and operatively connected with an

axle of the vehicle, a gear on the horizontal shaft in mesh with a gear on the vertical shaft, 30 and a second gear on the horizontal shaft, in mesh with a horizontal rack on the vehicle-frame, whereby the motor carried by the platform effects the rotation of the platform and propels the vehicle as well as operates the dredging apparatus.

5. The combination with a vehicle, of a vertically and horizontally swinging boom, carried thereby, a footboard extending along the boom to near its peak, a suction-pump carried 40 by the vehicle, a suction-pipe carried by the boom, and connected with the suction-pump, and provided near the peak of the boom with an oscillating section, and means arranged near the peak of the boom for swinging said section, and means carried by the vehicle for swinging the boom and for operating the suction-pump; substantially as described.

In testimony whereof we affix our signatures in presence of two witnesses.
